UNITED STATES PATENT OFFICE.

THOMAS WILLIAM BURR, OF STONEHAM, MASSACHUSETTS.

VACUUM-FEED CARBURETER.

1,271,848.

Specification of Letters Patent.

Patented July 9, 1918.

Application filed June 30, 1916. Serial No. 106,935.

To all whom it may concern:

Be it known that I, THOMAS W. BURR, a citizen of the United States, residing at Stoneham, in the county of Middlesex and 5 State of Massachusetts, have invented an Improvement in Vacuum-Feed Carbureters, of which the following is a specification.

This invention relates to certain improvements in carbureters for internal combustion 10 engines, and more particularly to carbureters employing a vacuum feed, as distinguished from a gravity feed.

Prior to my invention, various forms of 15 vacuum feed devices have been produced, which are designed to give a constant feed to the carbureter, irrespective of the height of the liquid in the main supply tank, but these devices have generally been of expensive construction or unsatisfactory in their 20 operation in certain particulars.

The object of my invention is so to improve existing devices, of the general character above referred to, that the feed of the liquid to be carbureted will be as nearly uniform as possible, under all 25 conditions, and also, to simplify devices of this character so that the cost of manufacture may be substantially reduced.

In the accompanying drawings, in which an embodiment of my invention is shown,—

Figure 1 is a central vertical sectional 35 view of a carbureting apparatus, embodying my invention.

Fig. 2 is a sectional view on the line 2—2 of Fig. 1.

Fig. 3 is a sectional view on the line 3—3 40 of Fig. 1.

In the drawing, a main casing *a* of tubular form is provided, having an air intake passage *b* leading thereto at one side and adjacent its lower end, and an outlet passage *c* 45 which is connected to the intake manifold of the engine, said air intake passage having the usual spring-pressed check valve *d*, and being connected to a pipe *e*, which preferably leads from about the exhaust manifold, so that the air is heated as it is drawn in. The outlet passage is provided with a throttle *f* of common form.

According to my invention, I provide an air-tight, or a closed receptacle *g* in the casing *a*, which is preferably mounted on a base *g'*, threaded into the lower end of said

casing, said receptacle being of tubular form and of substantially less diameter, externally, than the internal diameter of the casing, so that an annular space is provided 60 therebetween, into the lower end of which said air-inlet-passage leads. A conically shaped nozzle *h* is threaded into the upper end of said receptacle *g*, said nozzle having a tubular portion *h'* adapted to depend in 65 said receptacle for a short distance. A needle valve *i* is threaded into the bottom of the receptacle *g*, and is arranged in alignment with the passage through the tube *h'*, and in position to seat in the end of said 70 tube, to vary the size of the passageway therethrough. A suitably vented supply tank *j* for the liquid fuel, or gasoline is arranged below the level of the upper end of the receptacle *g*, and is connected thereto by 75 a supply pipe *k*, which depends therein to a point adjacent its bottom and extends upwardly through the casing *a* and into the receptacle *g* closely adjacent its upper end, and at a point above the level of the lower 80 end of the depending tube *h'*, so that, when the receptacle *g* is filled to the level of the point of entrance of the pipe *k* therein, the lower end of the pipe *h'* will be sealed. A clean-out cap *m* may be provided on the upper 85 end of the casing *a* to permit ready access to the nozzle *h*, for cleaning purposes.

The operation of the above-described device is as follows:—

As before stated, the casing *a* is connected 90 to the intake manifold of the engine, or directly to an engine cylinder, so that when the engine is turned over by hand, or by a self-starting device, a partial vacuum will immediately be formed within said casing, 95 and, as the receptacle *g* is in open communication therewith through the nozzle *h*, the air pressure will also immediately be reduced in said receptacle to such an extent that the atmospheric pressure on the surface of the liquid in the main supply tank *j* will force the liquid therein up through the pipe *k* into receptacle *g*, which will soon become filled to the level of the lower end of the pipe *h'*, so that the liquid will be forced 100 up said pipe *h'*, and discharged through the nozzle *h* into the casing *a*, this action continuing so long as a partial vacuum is maintained in the casing by the engine.

As the jet of liquid which will be discharged from the nozzle *h* is directed vertically upward, it will fall in a spray at all

sides of the receptacle, the upper end of the casing acting as a deflector to break up the drops of liquid. To cause the liquid falling on the top of the receptacle *g* to be readily discharged into the space about it, its top is made in conical form, as shown.

The suction action of the engine operates to lift the check valve *d* and draw air into and through the casing in the usual manner, 10 so that, as the air passes up through the casing it meets the falling spray of liquid from the nozzle, and becomes thoroughly mixed therewith, and the carbureting operation is effectively performed. The tension of the 15 spring *n* which holds the check valve *d* against its seat is so adjusted by the screw *o* that the air pressure necessary to lift it from its seat is greater than that necessary to force the liquid from the main tank into 20 the receptacle *g*, and into the casing *a*, so that the vacuum which is formed in the casing *a* will always be sufficient to cause the discharge of the liquid from the nozzle *h*.

In practice, the partial vacuum created 25 in the receptacle *g* will be sufficient to cause enough additional liquid to flow from the tank *j* to fill said receptacle to a level at which the lower end of the pipe *h'* will be constantly sealed to the depth of about one- 30 eighth of an inch. As the engine continues to operate, the conditions thus established will be constantly maintained, the liquid being discharged constantly through the nozzle *h* with sufficient rapidity to meet the 35 requirements of the engine and the rapidity of the discharge varying according to the speed of the engine, increased speed of the engine increasing the extent of the vacuum, and thus increasing the rapidity of discharge 40 through nozzle *h*.

As previously stated, the air which is drawn in through the pipe *e* is preferably heated from the exhaust, and the air inlet port is so arranged that the heated air is 45 caused to pass into the lower portion of the annular space about the receptacle *g*, so that it will have a tendency to heat the liquid therein, as it passes upward in the casing. As a result, after the engine has been operating 50 for a short time, the liquid will be heated to a substantial extent before it is mixed with the air, so that the carbureter will be more effective and efficient, it being a known fact that if the temperature of gasolene is 55 raised to a substantial extent above ordinary temperatures before it is vaporized, the vaporization will be much more nearly perfect than it would be at the lower temperature.

60 After the needle valve *i* has been properly adjusted for a normal speed of engine, further adjustment thereof will, ordinarily, be unnecessary and the operation will be entirely automatic, and dependent on the speed 65 of the engine.

As a constant balance is maintained, while the engine is running, between the air pressure within the casing *a*, and the atmospheric pressure within the tank *j*, a constant flow of liquid from the tank *j* into the receptacle *g* 70 will be caused, said flow being practically the same in amount as the amount discharged from the nozzle, and this amount will not be substantially affected by variations in the level of the liquid in the tank *j*, as 75 the air pressure in the top of the receptacle will be automatically decreased as the liquid level in the tank is reduced, although this pressure will be maintained, when the engine is operating, at some point which is less than 80 atmospheric pressure, but greater than that in the casing. It is, therefore, possible to locate the main reservoir at a considerable distance below the level of the carbureter, provided the spring tension on the air check 85 valve *d* is properly adjusted.

By having the inlet pipe *k* enter the receptacle above the level to which the latter may be filled, all possibility that the pipe *k* may act as a siphon, when the engine is at 90 rest, so as to withdraw the liquid from the receptacle, is avoided, so that after the receptacle has been once filled sufficiently to seal the end portion of the tube *k'*, liquid will be drawn from the receptacle as soon 95 as the engine is turned over. The receptacle thus acts as a supplemental liquid fuel reservoir, for two purposes, viz, to provide an immediate supply of liquid, when the engine is turned over, and to provide a means 100 whereby the liquid may be heated by the air to be carbureted, so that more efficient carburation and increased freedom of discharge may be secured, these purposes being, in a sense, incidental to the more important 105 feature of the provision of efficient and effective means for causing the engine, by its suction action, to draw the fuel from a tank located at a lower level than the carbureter, and for avoiding the necessity of employing 110 a float operated valve to control the feed of the liquid fuel to the carbureter.

I claim:—

1. In combination with a carbureter having a low-pressure chamber, a low-level, 115 main, liquid-fuel reservoir, a closed auxiliary reservoir, adapted to permit a partial vacuum to be maintained therein, a liquid supply pipe leading from a low level in said main reservoir and opening into said auxiliary reservoir at a higher level than 120 its bottom, and liquid discharging means, providing the sole means of communication between said auxiliary reservoir and said low pressure chamber, and having its inlet 125 opening to said auxiliary reservoir at a lower level than that at which said supply pipe opens thereto and having its outlet opening into said chamber at a higher level than that of its inlet.

2. In combination with a carbureter having a low pressure chamber, a low-level, main, liquid-fuel reservoir, a closed auxiliary reservoir, a liquid supply pipe leading from a low level in said main reservoir and opening into said auxiliary reservoir adjacent its top, and a fuel discharge pipe providing the sole means of communication between said auxiliary reservoir and 10 said chamber, and having its inlet opening to said auxiliary reservoir at a lower level than at which said supply pipe opens thereto and having its outlet opening into said chamber at a higher level than that 15 of its inlet.
3. A carbureter comprising a casing having a hot-air inlet-port at its lower end and a suction port at its upper end, an air-tight receptacle disposed within said casing to provide a surrounding chamber between the exterior of the receptacle and the interior of the casing and to the lower and upper ends of which said inlet and discharge ports respectively lead, a liquid-fuel-reservoir having a supply pipe leading therefrom at a point below the liquid level therein and opening into said receptacle at a point above said liquid level and adjacent the upper end of said receptacle, and 25 a discharge tube leading from said receptacle at a point below the discharge end of said supply pipe and opening into said casing above the top of said receptacle.
4. A carbureter comprising an upright tubular casing having an air-inlet port and a suction port in its side walls adjacent its lower and upper ends respectively, a tubu- 30 lar-air-tight receptacle disposed within said casing and having its bottom closing the lower end of said casing and providing an annular space between its walls and the walls of the casing, a discharge tube extending through the top of said receptacle and depending therein, a reservoir having a supply pipe connected thereto adjacent its bottom and connected to said receptacle above the lower end of said tube, and a needle valve extending through the bottom of said receptacle and arranged in operative relation to the lower end of said tube, 35 to vary the liquid flow therethrough.
5. A carbureter comprising an upright tubular casing having an air-inlet port at its lower end and a suction port at its upper end, a similarly-shaped, air-tight receptacle disposed within said casing and providing an annular space between its walls and the walls of said casing, a discharge nozzle extending vertically from the middle of the top of said receptacle and 40 having a tube connected thereto and depending into said receptacle, and a liquid-fuel-reservoir having a supply pipe connected thereto at a point below the liquid level therein and extending upwardly and 45 connected to said receptacle above said liquid level and above the lower end of said depending tube.

In testimony whereof I have signed my name to this specification.

THOMAS WILLIAM BURR.
